DESIGN FOR A COMBINED ASH TRAY AND
PIPE SMOKER'S ACCESSORY

Philip S. Harper, Chicago, Ill., assignor to Harper-Wyman Company, Chicago, Ill., a corporation of Illinois

Application June 24, 1946, Serial No. 130,982

Term of patent 14 years

(Cl. D85—2)

To all whom it may concern:

Be it known that I, Philip S. Harper, a citizen of the United States, residing at Chicago, in the county of Cook and State of Illinois, have invented a new, original, and ornamental Design for a Combined Ash Tray and Pipe Smoker's Accessory, of which the following is a specification, reference being had to the accompanying drawing, forming part thereof.

Fig. 1 is a top plan view of a combined ash tray and pipe smoker's accessory embodying my new design; and

Fig. 2 is a side elevational view of a combined ash tray and pipe smoker's accessory.

I claim:

The ornamental design for a combined ash tray and pipe smoker's accessory, as shown.

PHILIP S. HARPER.
